PAIR OF GOGGLES

John D. Hill, Rocky River, Ohio

Application December 15, 1952, Serial No. 22,715

Term of patent 14 years

(Cl. D57—1)

To all whom it may concern:

Be it known that I, John D. Hill, a citizen of the United States and a resident of Rocky River, Cuyahoga County, Ohio, have invented a new, original, and ornamental Design for a Pair of Goggles, of which the following is a specification, reference being had to the accompanying drawings, forming a part hereof.

Fig. 1 is a perspective view of a pair of goggles, showing my new design;

Fig. 2 is a fragmentary top plan view thereof; and

Fig. 3 is a fragmentary side elevational view, the opposite side being the same.

I claim:

The ornamental design for a pair of goggles, substantially as shown and described.

JOHN D. HILL.
